FACE SHIELD

Charles R. Jageman, 2710 W. 31st St.,
Erie, Pa. 16506

Filed Sept. 3, 1971, Ser. No. 177,921

Term of patent 14 years

Int. Cl. D28—03

U.S. Cl. D86—10 A

FIG. 1 is a perspective view of a face shield showing my new design;

FIG. 2 is a reduced scale side elevational view thereof.

I claim:

The ornamental design for a face shield, as shown and described.
